(57) **CLAIM**

The ornamental design for stand for pen or pens, as shown and described.

DESCRIPTION

FIG. 1 is a perspective view of a first embodiment of the stand for pen or pens of the present invention;

FIG. 2 is a front elevation view thereof;

FIG. 3 is a right side elevation view thereof;

FIG. 4 is a rear elevation view thereof;

FIG. 5 is a top plan view thereof;

FIG. 6 is a bottom plan view thereof;

FIG. 7 is a perspective view of a second embodiment of the stand for pen or pens of the present invention;

FIG. 8 is front elevation view thereof;

FIG. 9 is a right side elevation view thereof;

FIG. 10 is a rear elevation view thereof;

FIG. 11 is a top plan view thereof;

FIG. 12 is a bottom plan view thereof;

FIG. 13 is a perspective view of a third embodiment of the stand for pen or pens of the present invention;

FIG. 14 is a front elevation view thereof;

FIG. 15 is a right side elevation view thereof;

FIG. 16 is a rear elevation view thereof;

FIG. 17 is a top plan view thereof; and,

FIG. 18 is a bottom plan view thereof.

Those portions of the drawings rendered in phantom lines are shown for illustrative purposes only and form no part of the claimed design.
